E.W. Anderson

UNITED STATES PATENT OFFICE.

WILLIAM HENRY GARLOCK, OF SEATTLE, WASHINGTON.

CHOCK-BLOCK FOR LOGGING-TRUCKS.

SPECIFICATION forming part of Letters Patent No. 424,287, dated March 25, 1890.

Application filed December 23, 1889. Serial No. 334,649. (No model.)

To all whom it may concern:

Be it known that I, WILLIAM HENRY GARLOCK, a citizen of the United States, and a resident of Seattle, in the county of King and State of Washington, have invented certain new and useful Improvements in Chock-Blocks for Logging-Trucks; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a perspective view. Fig. 2 is a front elevation, and Fig. 3 is a detail view.

This invention relates to certain improvements in chock-blocks for logging-trucks; and it consists of the novel combination and construction of parts, as will fully appear from the following description and accompanying illustration.

In carrying out my invention I employ a base-plate A, having at short intervals apart stops b, and which is adapted to rest upon the bolster B of the truck, and, also, which is formed or cast with drop-lugs A', having inward upturned lower ends a, which engage the bottom edges of the bolster. From the under side of the base-plate A depend short, stout, parallel projections or studs b', which engage the inner sides of the upper edges of the bolster B, and thus prevent lateral displacement of the base-plate A. Upon the upper side or surface of the plate A is cast the block or chock C proper, which has an upper convex or inclined surface sloping from its outer perpendicular edge inward, with its lower tapering end at the base-plate, which convex or inclined surface is presented, toward and against which rests the log on the truck in transit. The chock or block C is connected or chained, as at d, to the truck-bolster on the under side, keeping the chock or block always at hand.

D is a dog pivoted at one end, preferably by a tubular boss e integral therewith, to the upper side of the base-plate A, near one side edge, said boss receiving a pivot or projection e', extending from an elevation on the base-plate.

The dog D is adapted, as clearly shown, to stand between the upper side edges of the bolster B and upon the depressed surface of bolster and against an adjacent stop of said surface, thus preventing endwise displacement of the chock or block by the pressure of the log thereon. 55

In order to lock or secure the dog D from accidental upward displacement, I provide a latch D', which is similarly pivoted at its upper end to the perpendicular edge or end of the block or chock D and adapted to engage at its lower end the upper edge of the dog. 60

Having thus fully described my invention, 65 what I claim, and desire to secure by Letters Patent, is—

1. The chock-block for logging-trucks, having the dog, in combination with the logging-truck bolster having stops engaged by said dog at its lower edge, substantially as described. 70

2. In a chock-block for logging-trucks, the combination, with the bolster of the logging-truck, of the dog pivoted to the chock or block and engaging or fitting between the inner side edges of the bolster, substantially as specified. 75

3. In a chock-block for logging-trucks, the combination, with the bolster of the truck having a series of stops, of the dog engaging said stops and the latch engaging said dog, substantially as specified. 80

4. The combination, with the logging-truck bolster having a depressed surface provided with stops, of the dog adapted to engage or fit between the upper side edges of the bolster and engage said stops, substantially as set forth. 85

5. The combination, with the logging-truck bolster having the depressed surface provided with stops, of the dog adapted to fit between the upper side edges of the bolster and engage said stops, and the latch engaging said dog, substantially as specified. 90

6. The combination, with the logging-truck bolster, of the chock or block having the drop-lugs provided with inward upturned lower ends engaging the lower side edges of said bolster, substantially as set forth. 95

7. The combination, with the logging-truck bolster, of the chock or block provided with 100

drop-lugs having inward upturned lower ends, said chock or block also having pendent studs or projections fitting against the inner sides of said bolster, substantially as specified.

5 8. The chock-block for logging-trucks, consisting of the base-plate having a chock or block provided with an upper convex or inclined surface, the drop-lugs having inward upturned lower ends, the dog having the

lower engaging edge, and the latch pivoted to said block and adapted to engage said dog, substantially as set forth.

In testimony whereof I affix my signature in presence of two witnesses.

WILLIAM HENRY GARLOCK.
